TRACTOR SCRAPER

Harry Burney Thorpe, Visalia, Calif.

Application August 27, 1935, Serial No. 38,122

5 Claims. (Cl. 37—144)

This invention relates to scrapers for attachment to a tractor and which may be employed for bulldozing, etc., and an object of the invention is to provide a tractor of this character having improved means for mounting the scraper blade and also improved means for varying the angle of the blade with respect to the line of draft.

In accordance with the present invention, hydraulic means is provided for changing the angle of the blade whereby the blade can be easily and quickly changed at the will of the operator thereby tending to save a great deal of time and expense in the operation thereof and obviates the necessity of backing up or exchanging the blade by hand.

The invention together with its objects and advantages will be best understood from a study of the following description taken in connection with the accompanying drawings wherein:

Figure 1 is top plan view illustrating the application of the invention to a tractor.

Figure 2 is a detail view taken substantially on the line 2—2 of Figure 1.

Figure 3 is an enlarged detail sectional view taken through a guide cylinder and piston assembly.

Figure 4 is a detail sectional view taken substantially on the line 4—4 of Figure 2.

Figure 5 is a plan view of a reciprocating rod.

Figure 6 is a view similar to Figure 5 showing the reciprocating rod connected with one end of the piston rod.

Figure 7 is a detail view taken substantially on the line 7—7 of Figure 2.

Figure 8 is a detail view taken substantially on the line 8—8 of Figure 1.

Figure 9 is an enlarged longitudinal sectional view through the guide member and reciprocating rod assembly.

Figure 10 is a detail view taken substantially on the line 10—10 of Figure 2.

Figure 11 is a detail view taken substantially on the line 11—11 of Figure 5.

Figure 12 is a fragmentary detail sectional view taken on the line 12—12 of Figure 11.

Figure 13 is an elevational view of a portion of a cable structure.

Referring to the drawings by reference numerals it will be seen that the improved bulldozer comprises a blade 1 that is of conventional construction and is provided on its rear side with hinge brackets 2 whereby through the medium of the hinge pins 3 the blade is connected with one end of reciprocating rods 4.

Intermediate its ends the blade 1 at the rear side thereof is provided with a similar bracket 5 whereby through the medium of a hinge pin 6 the blade is connected to a headed rod 7 operating through a suitable guide in the cross frame member 8 at the front of the tractor indicated generally by the reference numeral 9. Suitable spring means 10 is provided for normally urging the blade 1 in a forward direction.

Provided at opposite sides of the tractor are substantially tubular guide members 11, 11 in one of which is secured by suitably anchored blocks 12 and as best shown in Figure 3, a cylinder 13 in which operates piston 14 provided with rod 15.

The piston rod 15 is connected with a slide rod 4 through the medium of a coupling indicated generally by the reference numeral 16. Each rod 4 is provided with such a coupling 16.

As shown in Figure 10, each coupling 16 is in the form of a block provided with a recess 17 opening through opposite sides of the block and through the top of the block. For the recess 17 there is provided a cover 18a secured to the block by any suitable fastening means.

Arranged in the recess 17 are a pair of oppositely swinging dogs 18 normally urged outwardly through the medium of a spring 19. For drawing these dogs inwardly of the recess against the action of spring 19 there is provided a cable 20 whose respective opposite ends are trained over suitable arranged pulleys 21 journaled within the recess 17 and connected to the dogs 18 as best shown in Figure 10. Intermediate its ends the cable 20 is connected as at 22 with a main cable 23 that extends to and is suitably connected with a control lever 24 mounted on the tractor.

The cables 23 extend upwardly through suitable substantially conical shaped housings 25 secured to the cover plates 18a of the blocks and accommodated in slots 27 provided in the top of the guide tubes 11.

Cooperable with the dogs 18 for securing the rods 4 at the desired projected or retracted position are suitably shaped notches 28 and 29 arranged in pairs internally of the guide tubes 11 as best shown in Figure 9. As also shown in Figure 9 suitable guide blocks 30 are provided for the rods 4. It will thus be seen that with the dogs 18 in the projected position shown in Figure 10 and engaged in the notches 28 the rods 4 will be held in a projected position; on the other hand with the dogs 18 engaged in the notches 29 rods 4 will be held in a retracted position. To release the dogs from the notches 28 or 29 as the

case may be, lever 24 is operated for exerting a pull on the cables 23 and associated cables 20 for drawing the dogs 18 inwardly against the action of springs 19 thus freeing the rods 4 to permit the latter to move inwardly or outwardly depending upon which end of the cylinder 13 is being charged with fluid for operating the piston 14.

In the present instance but one cylinder 13 is provided and at its respective opposite ends is 10 equipped with caps 31, 32 into which are tapped nipples 33, 34. The nipples 33, 34 are connected by flexible conduits 35, 36 with a suitable source of fluid supply indicated generally by the reference numeral 37 and arranged in these conduits 15 35, 36 is a suitable control valve 38. It will thus be seen that to swing the blade 1 from the transverse position shown in Figure 1 to, for example, the dotted line position shown in said figure, valve 38 is manipulated to permit a supply of 20 oil or the like under pressure to the cylinder 13 at the cap equipped end 32. The oil entering the cylinder will then act on the piston 14 to cause the same to move forwardly upon release of the dogs 18 from the notches 28. In this manner, 25 the blade 1 will be moved to the dotted line position shown in Figure 1 and when this position is attained the dogs 18 move opposite to and swing outwardly into engagement with the notches 28 for locking the rod 4 at the near side of the tractor in projected position. In this connection it 30 will be understood that the rod 4 at the opposite side will move in a reverse direction or to the right in Figure 1 to assume the dotted position shown in Figure 1. Thus it will be seen that the 35 blade 1 may be swung to a position diagonal to the line of draft and either to the right or left in a quick and efficient manner.

To allow for the movement of the blade to the desired angular position the guide tubes 11 at 40 their rear ends are pivoted to a frame F suitably mounted on the tractor as clearly shown in Figure 2. In this connection it will be noted that to the rear end of each guide sleeve 11 there is suitably connected a tubular extension 39 which 45 at one end is pivoted to the frame F through the medium of a pivot pin 40. The tube extension 39 is provided with upper and lower slots to accommodate the pivot pin 40 and arranged in the tube as best shown in Figure 4 is a block 41 having an arcuate notch in one edge to engage the pin 40 as shown. This block 41 is normally urged into engagement with the pin 40 through the medium of a suitable coil spring 42. Thus an efficient pivotal connection between each guide tube 11 and the frame F is provided permitting the necessary swinging movement of the guide tubes incidental to a change in the angular position of the blade 1 relative to the line of draft.

It is thought that a clear understanding of 60 the invention will be had from the foregoing and that it will be appreciated that a scraper of this character may be readily and easily mounted on a tractor and will be efficient in operation for the purpose intended.

Having thus described the invention, what is 65 claimed as new is:

1. The combination with a tractor, of a thrust pin slidably mounted at the forward end of the tractor, a spring device connected with the thrust

pin and normally urging the same forwardly with reference to the tractor, a scraper blade pivoted intermediate its ends to the thrust pin, a pair of guide tubes, spring cushioned devices pivotally connecting the guide tubes at one end thereof to the tractor at opposite sides of the latter, slide rods having ends slidably working in the guide tubes and outer ends pivotally connected with the scraper blade, hydraulic means connected with the slide rods for reciprocating the latter, and means for holding the guide rods at the desired projected or retracted position.

2. In combination with a tractor, a frame carried thereby, a pair of guide tubes disposed on the tractor at opposite sides of the tractor and pivoted at one end to the frame, slide rods having ends mounted for reciprocation within the guide tubes, a scraper blade pivoted to the outer end of the slide rods, each of said guide tubes being provided with longitudinally spaced pairs of opposed notches, and spring pressed dogs pivotally mounted on each of the slide rods and adapted to engage the notches of a selected pair for holding the slide rods at the desired adjustment.

3. In combination with a tractor, a pair of guide tubes disposed one to each side of the tractor and pivotally mounted at one end of the tractor, slide rods having ends slidably working within said guide tubes, a scraper blade pivoted to the free ends of said slide rods, a cylinder mounted in at least one of said guide tubes, a piston mounted for reciprocation in said cylinder and having a rod connected with a slide rod, hydraulic means connected with the cylinder for reciprocating the piston for varying the angle of the scraper blade with respect to the line of draft, and latch means associated with each slide rod and its guide tube whereby the guide rods may be selectively secured at the desired adjustment.

4. In combination with a tractor, a frame carried thereby, a thrust pin slidably mounted on the forward end of the frame, a scraper blade pivotally mounted on the free end of the thrust pin, a pair of guide tubes disposed one to each side of the tractor and pivotally connected at one end to the frame, slide rods having ends slidably working in said guide tubes and free ends pivotally connected with the scraper blade, hydraulic means for reciprocating said slide rods, and latch means for securing the slide rods at the desired projected or retracted position for securing the blade at the desired angle relative to the line of draft.

5. In combination with a tractor, a scraper blade pivotally mounted on the tractor at the forward end of the latter, and means for swinging the blade to a desired angle with respect to the line of draft, said means including a guide tube, a slide rod having an end slidably working in the guide tube and a second end hinged to the scraper blade, interengaging means on said guide tube and said slide rod for securing the latter in either a projected or retracted position optionally, a cylinder mounted in the guide tube, a piston mounted for reciprocation in the cylinder, and said piston having a rod rigidly connected with the slide rod for transmitting movement of the piston to the slide rod.

HARRY BURNEY THORPE.
